UNITED STATES PATENT OFFICE.

ROBERT STOCK, OF SILVER CREEK, NEW YORK.

SPRING-WHEEL.

1,031,098.

Specification of Letters Patent.

Patented July 2, 1912.

Application filed September 14, 1910. Serial No. 581,935.

To all whom it may concern:

Be it known that I, ROBERT STOCK, a citizen of the United States, residing at Silver Creek, in the county of Chautauqua and State of New York, have invented new and useful Improvements in Spring-Wheels, of which the following is a specification.

The object of this invention is the production of a spring wheel which is as resilient as the pneumatic wheels now in common use and which is very durable, not liable to get out of order, and of such construction that the same can be readily assembled and dismembered and manufactured at comparatively low cost.

In the accompanying drawings: Figure 1 is a side elevation, partly in section, of my improved spring wheel. Figs. 2 and 3 are fragmentary cross sections of the same in the correspondingly-numbered lines in Fig. 1. Fig. 4 is a plan view of several of the supporting shoes of the wheel.

Similar letters of reference indicate corresponding parts throughout the several views.

The relatively fixed parts of the improved wheel comprise a hub A, an annular rim B arranged concentrically with the hub, and a plurality of radial spokes C connected at their inner ends with the hub and at their outer ends with the rim. Each of the spokes is preferably made hollow or of tubular form for the purpose to be presently described.

D, D' represent a plurality of inner and outer supporting shoes which are arranged in an annular row around the rim and each of which is preferably constructed of outwardly-dished form of sheet metal, so that the same has some resilience. The inner supporting shoes alternate with the outer supporting shoes and each outer shoe laps at its opposite ends over the adjacent ends of the two inner shoes on opposite sides of the respective outer shoe.

E represents a plurality of main radial slide or guide rods each of which is connected at its outer end to the central part of an inner shoe and arranged at its inner end in one of the hollow spokes while its central part passes through an opening f in the rim in line with the respective spoke. At its inner end the main slide rod is provided with a collar e forming a shoulder which bears against the outer end of a spiral inner main spring g arranged within the spoke, the inner end of said spring resting

against the hub. The collar e is larger than the opening f and therefore operates as a stop for limiting the outward movement of the main rod E under the action of the spring g. The collar e is preferably adjustably secured to the guide rod E by providing the same with an internal screw thread and engaging the same with an external screw thread on the guide rod, as shown in Figs. 1 and 2. By adjusting the collars e outwardly or inwardly on the rods E, the tension of the springs G may be regulated so that the load is distributed uniformly over the springs and any difference in the tension of these springs when manufactured is compensated for.

G represents a pair of spiral outer main springs interposed between the ends of each inner shoe on opposite sides of its slide rod and the adjacent part of the periphery of the rim. These outer main springs together with the inner main springs serve to hold the inner shoes in their outward or projecting position and yieldingly support the load which is imposed on the same.

H represents a plurality of auxiliary radial slide or guide rods which alternate with the main slide rods and each of which is secured at its outer end to the central part of an outer shoe while its inner end is arranged in an opening i formed in the rim between two spokes thereof. Each of the auxiliary guide rods is surrounded by an auxiliary spiral spring J which bears at its outer end against the inner side of the respective outer shoe while its inner end bears against the periphery of the rim. The outward movement of each outer shoe and the expansion of its companion spring J is limited by a cap or hollow cup-shaped stop collar j arranged on the inner end of the auxiliary slide rod and bearing against the inner side of the rim. The collar j is preferably adjustably connected with the slide rod H so as to permit shifting the collar lengthwise of the rod H and thus adjust the tension of the several springs of the wheel. This adjustability of the collar j may be obtained by various means, for instance, as shown in Figs. 1 and 2, by a screw stem k projecting outwardly from the inner side of the collar j and entering a threaded opening in the end of the auxiliary slide rod. Upon tightening the collar j the outer shoes are drawn inwardly and the latter in turn draw the inner shoes inwardly, thereby increasing the

2

tension on the several springs, whereby the same are stiffened and better adapted for supporting heavy loads, while upon loosening said collars the springs are permitted to 5 expand more fully and therefore become softer in which condition they are better suited for carrying light loads. As the wheel rotates the several shoes around the rim are pressed inwardly as the load is 10 brought to bear successively on the shoes and as the shoes are relieved from the load the same are again projected by the load. Owing to the several shoes overlapping each other in the manner shown; the pressure of the 15 load is brought to bear gradually on each shoe and a practically continuous support is provided on the ground, so that the wheel runs smoothly and uniformly without any jarring in substantially the same manner as 20 in wheels having continuous pneumatic tires.

In order to permit the slide rods of the inner and outer shoes to rock slightly as the pressure of the load is brought gradually 25 on the same, the openings in the rim which receive these rods are lined with bushings *m* of rubber or other elastic or flexible material, as shown in Figs. 1, 2 and 3. By this means the rods are free to slide in the rim as the 30 shoes are retracted and projected when the wheel is in operation, thereby preventing cramping of the rods in the rim and permitting the cushioning devices to operate freely at all times. For the purpose of still 35 further eliminating any unevenness in the surface of the wheel which bears on the ground an endless tire *L* of rubber, leather or other elastic or flexible material may be placed around the outer side of the shoes.

This tire may be channel-shaped in cross 40 section, so as to fit the shape of the shoes, as shown in Figs. 2 and 3, and thereby hold the tire against lateral displacement on the shoes. For convenience in applying or removing the tire from the shoes, the tire may 45 be split and the ends thereof scraped, as shown at *l*, which ends are overlapped and detachably secured to each other by rivets *l*, as shown, or by any other suitable means.

I claim as my invention:

A spring wheel comprising a hub, a rim, hollow spokes connecting the hub and rim, main guide rods passing through openings in the rim and having their inner ends arranged within the spokes, main springs arranged within the spokes and bearing against said main rods, inner supporting shoes connected with the outer ends of said main rods, outer supporting shoes bearing against the inner shoes, auxiliary guide rods 60 each secured at its outer end to one of the outer shoes and passing through an opening in the rim, and means for adjusting the tension of said springs comprising a hollow cup-shaped collar fitting over the inner end 65 of each auxiliary guide rod and bearing against the inner side of the rim, and a screw stem projecting outwardly from the inner side of said collar and engaging with a threaded opening in the inner end of said auxiliary guide rod.

Witness my hand this 10th day of September, 1910.

ROBERT STOCK.
